CLAIM

The ornamental design for a bedstead, as shown and described.

DESCRIPTION

FIG. 1 is a front, left and top perspective view of a bedstead, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, left and top perspective view of a second embodiment of a bedstead.

FIG. 10 is a rear, right and bottom perspective view of the second embodiment of the bedstead of FIG. 9.

FIG. 11 is a front elevation view of the second embodiment of the bedstead of FIG. 9.

FIG. 12 is a rear elevation view of the second embodiment of the bedstead of FIG. 9.

FIG. 13 is a left side elevation view of the second embodiment of the bedstead of FIG. 9.

FIG. 14 is a right side elevation view of the second embodiment of the bedstead of FIG. 9.

FIG. 15 is a top plan elevation view of the second embodiment of the bedstead of FIG. 9; and,

FIG. 16 is a bottom plan elevation view of the second embodiment of the bedstead of FIG. 9.

The dashed broken lines depict portions of the bedstead that form no part of the claimed design.
